(57) **CLAIM**

The ornamental design for a wall mounting assembly for storing pistols in an upright positioning, as shown and described.

DESCRIPTION

FIG. 1 is a front perspective view of a wall mounting assembly for storing pistols in an upright positioning, showing my new design;

FIG. 2 is a front elevation view thereof;

FIG. 3 is a rear elevation view thereof;

FIG. 4 is a left side elevation view thereof;

FIG. 5 is a right-side elevation view thereof;

FIG. 6 is a top plan view thereof; and,

FIG. 7 is a bottom plan view thereof.

The broken lines showing in the figures representing two pistols is for illustrative purposes only and forms no part of the claimed design.

1 Claim, 7 Drawing Sheets
